[57] CLAIM

The ornamental design for a fence section, as shown and described.

DESCRIPTION

FIG. 1 is a front elevational view of a fence section, the rear elevational view being identical, showing my new design. FIG. 2 is a right side elevational view thereof, the left side elevational view being identical.

FIG. 3 is a top plan view thereof; and,

FIG. 4 is a bottom plan view thereof.

The broken lines are for illustrative purposes only and form no part of the claimed design.
